J. Drayton,

Bedstead Fastening.

No. 11,722.

Patented Sep. 26, 1854.

UNITED STATES PATENT OFFICE.

JOHN DRAYTON, OF BUFFALO, NEW YORK.

BEDSTEAD-FASTENING.

Specification of Letters Patent No. 11,722, dated September 26, 1854.

To all whom it may concern:

Be it known that I, JOHN DRAYTON, of the city of Buffalo, in the county of Erie and State of New York, have invented a new and Improved Mode of Fastening the Posts of Bedsteads to the Rails and also Fastening the Head and Foot Boards to the Posts; and I do hereby declare that the following is a full, clear, and exact description thereof, 10 reference being had to the annexed drawings, making part of this specification, and to the letters of reference marked thereon, in which—

Figure 1, is a perspective view; Fig. 2, 15 shows a coupling of the side rail with the posts; Fig. 3 shows coupling end rail and foot and head board with the posts.

To enable others skilled in the art to make and use my invention, I will proceed to 20 describe its construction and operation. I construct the end rails with crooked, or curved tenons on each end, which fit into corresponding mortises in the posts, as shown at letter A in Figs. 1 and 3, so that these rails 25 cannot be connected, or disconnected with the posts without turning the posts, and of course cannot be disconnected while the side rails are in their places, and prevent the posts from turning. The side rails are 30 constructed with dowels, or tenons at each end fitting into corresponding openings in the

posts, as shown in letter G in Fig. 2 and the side rails and posts are drawn together by means of clamps and wedges, as shown in letters B and D in Fig. 2; one of the ears 35 of each clamp being fitted into a mortise made for that purpose, in the face of the post, as is shown at letter C in Fig. 2 and the other ear entering a large mortise or opening in the face of the rail, as shown in 40 letter H in Fig. 2, the wedge is driven through the rail, and behind the last mentioned ear, as shown at letters H and D in Fig. 2 thus drawing the rail and post tightly together, and preventing the post from turning, 45 as shown in letters B and D in Fig. 1.

The end boards are secured to the posts by means of a dovetail tenon, at each end of the board, fitting a corresponding opening in the post, as shown in letter E Figs. 1 and 3. 50

What I claim as my invention, and desire to secure by Letters Patent, is—

The manner of fastening the end rails to the posts by means of the curved or crooked tenons, in combination with the clamp and 55 wedge for securing the side rails to the posts as described.

JOHN DRAYTON.
